(57) CLAIM

The ornamental design for a display case, as shown and described.

DESCRIPTION

FIG. 1 is a perspective view of the left side, front and top of a display case incorporating my new design. The front vertical surface at the back of the shelves of the display case is mirrored.

FIG. 2 is a front elevational view thereof.

FIG. 3 is a right-side elevational view thereof, with the left-side elevational view thereof being a mirror image.

FIG. 4 is a rear elevational view thereof; and,

FIG. 5 is a top plan view thereof, with the bottom plan view thereof being a mirror image.

The broken lines of a base for the display case shown in FIGS. 1-4 are for illustrative purposes only and form no part of the claimed design.
